(57) CLAIM

The ornamental design for a shirt with inner garment, as shown and described.

DESCRIPTION

FIG. 1 is a front perspective view of a shirt with inner garment right side out;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front perspective view of the shirt, wherein the shirt with inner garment has been turned inside-out;

FIG. 9 is a front elevational view thereof;

FIG. 10 is a rear elevational view thereof;

FIG. 11 is a right side elevational view thereof;

FIG. 12 is a left side elevational view thereof;

FIG. 13 is a top plan view thereof;

FIG. 14 is a bottom plan view thereof;

FIG. 15 is a front perspective view of a shirt with inner garment showing the inner garment right-side out in isolation;

FIG. 16 is a front elevational view thereof;

FIG. 17 is a rear elevational view thereof;

FIG. 18 is a right side elevational view thereof;

FIG. 19 is a left side elevational view thereof;

FIG. 20 is a top plan view thereof; and,

FIG. 21 is a bottom plan view thereof.

The broken lines shown in the figures are included for the purposes of illustrating portions of the shirt with inner garment which form no part of the claimed design.

1 Claim, 18 Drawing Sheets
